COMBINED ANDIRON AND FIRE LIGHTING IMPLEMENT

Carl G. Björnerantz, Evanston, Ill.

Application June 10, 1954, Serial No. 30,918

Term of patent 14 years

(Cl. D81—6)

Fig. 1 is a side perspective view of the combined andiron and fire fighting implement embodying my new design;

Fig. 2 is a perspective view of the andiron shown in Fig. 1;

Fig. 3 is a slightly enlarged perspective view of the fire lighting implement shown in Fig. 1; and

Fig. 4 is a side elevational view of the combined article shown in Fig. 1 on a reduced scale.

I claim:

The ornamental design for a combined andiron and fire lighting implement, as shown.
